UNITED STATES PATENT OFFICE.

WALFRID WALLENTHIN, OF ATTLEBORO, MASSACHUSETTS, ASSIGNOR TO
BATES & BACON, OF ATTLEBORO, MASSACHUSETTS, A FIRM.

FASTENER.

SPECIFICATION forming part of Letters Patent No. 739,522, dated September 22, 1903.

Application filed April 27, 1903. Serial No. 154,548. (No model.)

To all whom it may concern:

Be it known that I, WALFRID WALLENTHIN, a citizen of the United States, residing at Attleboro, in the county of Bristol and State of Massachusetts, have invented a new and useful Improvement in Fasteners, of which the following is a specification.

This invention has reference to an improvement in fasteners used to fasten or secure articles to wearing-apparel or to fasten articles of wearing-apparel together. In fasteners or clamps of this nature as heretofore constructed the fastening or clamping arm is constructed separately and secured in the frame of the fastener.

The object of my invention is to construct the frame and clamping-arm integral, thus simplifying the construction and lessening the cost of the fastener.

My invention consists in the peculiar and novel construction of the frame and clamping-arm, formed integral, and of the operating-lever, pivotally secured in the frame and operating the clamping-arm, as will be more fully set forth hereinafter.

Figure 1 is an enlarged plan view of the blank forming the frame and clamping-lever in one piece. Fig. 2 is an edge view of the frame and clamping-lever blank. Fig. 3 is a plan view of the operating-lever. Fig. 4 is an edge view of the operating-lever. Fig. 5 is a view of the completed fastener looking at the operating-lever side. Fig. 6 is a sectional view taken lengthwise through the fastener and showing the fastener in the closed position. Fig. 7 is a sectional view similar to Fig. 6, showing the fastener in the normal open position in full lines and in the extreme open position in broken lines.

In the drawings, *a* is the U-shaped frame of the fastener stamped from sheet metal having a spring-tension. The frame *a*, with the eyes *a'* *a'* for attaching articles to the fastener, the stamped-up bearings *a²* *a²* for the pivots of the operating-lever, and the clamping-arm *a³*, with the inwardly-bent lip *a⁴* and the stamped-up hook *a⁵*, are formed integral. The operating-lever *b* is stamped from sheet metal and formed to have the outwardly-rolled edge *b'*, the pivots *b²* *b²*, and the inwardly-bent cam end *b³*.

To insert the operating-lever *b* in the frame, the blank is partly bent and the clamping-arm *a³* is depressed. The end *b³* of the operating-lever is now inserted in the opening of the blank, and the pivots *b²* *b²* are forced under and into the bearings *a²* *a²*, bringing the operating-lever into the position as shown in Fig. 7. The operation of bending the blank is now completed, forming the U-shaped frame *a* of the fastener.

In the operation of my improved fastener the end *b³* of the operating-lever acts as a cam on the clamping-arm *a³*, the closing of the operating-lever forcing the clamping-arm into its closed position against the spring-tension of the arm and holding it in this position, as shown in Fig. 6. When the operating-lever is opened, the clamping-arm (under spring-tension) assumes its normal open position, as shown in full lines in Fig. 7, and a backward movement of the operating-lever *b* brings the end *b³* under the hook *a⁵* and opens the clamping-arm to its outward limit, as shown in broken lines in Fig. 7.

By my improved construction I form a fastener of two parts that has all the characteristics of the best fasteners of this nature having three or more parts and at a lower cost than has heretofore been done.

Having thus described my invention, I claim as new and desire to secure by Letters Patent—

In a fastener, the combination with the U-shaped frame *a* stamped from sheet metal and having the eyes *a'* *a'*, the stamped-up bearings *a²* *a²*, and the clamping-arm *a³* with the inwardly-bent lip *a⁴* and the stamped-up hook *a⁵* all formed integral with the frame, of the operating-lever *b* stamped from sheet metal and having the outwardly-rolled edge *b'*, the pivots *b²* *b²* and the inwardly-bent cam end *b³*, all for the purpose as described.

In testimony whereof I have signed my name to this specification in the presence of two subscribing witnesses.

WALFRID WALLENTHIN.
